DYNAMOELECTRIC MACHINE

William A. Forsty, Franklin Township, Westmoreland County, Pa., assignor to Westinghouse Electric Corporation, East Pittsburgh, Pa., a corporation of Pennsylvania

Application December 10, 1958, Serial No. 53,718

Term of patent 14 years

(Cl. D26—5)

Fig. 1.

Fig. 2.

Fig. 1 is a perspective view of a dynamoelectric machine, showing my new design; and

Fig. 2 is an end elevational view thereof.

The dominant features of my new design are shown in solid lines in the drawing.

I claim:

The ornamental design for a dynamoelectric machine, substantially as shown and described.
